CLAIM

The ornamental design for a cutting tool, as shown and described.

DESCRIPTION

FIG. 1 is a front view of a cutting tool in accordance with the present design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a perspective view thereof; and,

FIG. 8 is an enlarged view of portion 8 of FIG. 7.

The broken lines shown in the drawings represent portions of the cutting tool that form no part of the claimed design. The dash dot dash broken lines on FIG. 7 are provided to define the enlargement region shown in FIG. 8 and form no part of the claimed design.

1 Claim, 7 Drawing Sheets
